UNITED STATES PATENT OFFICE.

JOHN LA PRELLE, OF AUSTIN, TEXAS.

DESIGN FOR A STAPLE.

SPECIFICATION forming part of Design No. 30,896, dated May 30, 1899.

Application filed May 8, 1899. Serial No. 716,024. Term of patent 14 years.

To all whom it may concern:

Be it known that I, JOHN LA PRELLE, a citizen of the United States, residing at Austin, in the county of Travis and State of Texas, 5 have invented and produced a new and original Design for a Staple, of which the following is a specification.

The invention relates to a new and original design for staples.

10 The essential feature of the design resides in a staple provided with series of barbs or spurs and intervening corrugations arranged in continuous series at the inner and outer edges of the staple.

15 A minor feature of the design resides in the tapered ends of the sides of the staple and the smooth faces between the spurs and corrugations.

20 In the drawings, Figure 1 is a perspective view of a staple, showing my new and original design. Fig. 2 is a side elevation of the same.

Referring to the drawings, in which like numerals of reference designate corresponding parts, 1 indicates a staple provided at its 25 inner and outer edges 3 and 4 with spurs or barbs and intervening corrugations arranged in continuous series, as clearly shown in Fig. 2, and presenting irregular inner and outer surfaces. The sides 3, which have their terminals tapered, are provided between the inner and outer spurs and corrugations with smooth faces 2.

30 What I claim is—

The design for a staple, herein shown and 35 described.

In testimony that I claim the foregoing as my own I have hereto affixed my signature in the presence of two witnesses.

JOHN LA PRELLE.
